UNITED STATES PATENT OFFICE.

HENRY MEIER, OF NEW YORK, N. Y.

DESIGN FOR A NURSING-NIPPLE.

SPECIFICATION forming part of Design No. 26,377, dated December 8, 1896.

Application filed September 29, 1896. Serial No. 607,375. Term of patent 14 years.

To all whom it may concern:

Be it known that I, HENRY MEIER, a citizen of the United States, residing in the city, county, and State of New York, have invented and produced a new and original Design for Nursing-Nipples, of which the following is a specification, reference being had to the accompanying drawings, forming a part of the same.

Figure 1 is a side view of my design for nipples. Fig. 2 is a central section of the same.

The leading features of my design consist of a collar *a* near the lower part of the nipple *b* and a flange *c* below said collar, a groove intervening. The flange *c* is larger in diameter than the collar *a*.

ter than the collar *a*. The groove or space *d* between the collar and flange is designed to carry a cap which fastens the nipple upon the neck of the bottle.

My design is intended to be cast or molded from rubber and vulcanized to the proper degree of elasticity.

Having now described my invention, what I claim is—

The design for nursing-nipples, substantially as shown.

HENRY MEIER.
